UNITED STATES PATENT OFFICE

THEODORE P. EICHELSDOERFER, OF ROCK ISLAND, ILLINOIS

DESIGN FOR A TROPHY PLAQUE

Application filed May 4, 1933. Serial No. 48,012. Term of patent 3½ years.

To all whom it may concern:

Be it known that I, THEODORE P. EICHELSDOERFER, a citizen of the United States, residing at Rock Island, in the county of Rock Island and State of Illinois, have invented a new, original, and ornamental Design for a Trophy Plaque, of which the following is a specification, reference being had to the accompanying drawing forming a part thereof, in which:

plaque, showing my new design, in which the frame is of imitation wood and the field imitation silver.

Figure 2 is a cross-section on the broken line 2—2 of Fig. 1.

I claim:

The ornamental design for a trophy plaque, as shown and described.

In testimony whereof, I affix my signature.

THEODORE P. EICHELSDOERFER.
